(57) **CLAIM**

The ornamental design for a bracket for shakleless padlock, substantially as shown and described.

DESCRIPTION

FIG. 1 is a top, front and right perspective view of a bracket for shakleless padlock showing our new design, shown in an assembled position;

FIG. 2 is an exploded perspective view thereof;

FIG. 3 is a front elevational view of the door mount portion of the bracket of FIG. 1;

FIG. 4 is a top plan view thereof;

FIG. 5 is a side elevational view thereof;

FIG. 6 is a back elevational view of the backing plate portion of the bracket of FIG. 1, the front view of the plate being the same;

FIG. 7 is a top plan view thereof;

FIG. 8 is a side plan view thereof;

FIG. 9 is a side plan view of the lower base mount portion of the bracket of FIG. 1;

FIG. 10 is a top plan view thereof; and,

FIG. 11 is an end plan view thereof.

The broken lines are for illustrative purpose only and form no part of the claimed design. The door mount (FIGS. 3-5) the backing plate (FIGS. 6-8) and lower base mount (FIGS. 9-11) portions of the design are shown separately for clarity.
